INCINERATOR WITH BURNER ASSEMBLY

John W. Hebert, Bay City, Mich., assignor to Calcinator Corporation, Bay City, Mich.

Application August 21, 1953, Serial No. 375,636

4 Claims. (Cl. 110—18)

This invention relates to gas-fired incinerators for burning refuse, garbage, trash and the like, and more particularly to downdraft incinerators and certain novel improvements in gas burner assemblies therefor.

One of the prime objects of the invention is to design a gas burner assembly for disposed units which incorporates a pre-mixing tube, the air ports of which are located outside the combustion chamber in the air supply passage so that only fresh clean air, without entrained fly ash or uncombusted particles, is mixed with the gaseous fuel supplied to the burner. Such a unit will mix fuel gas and air under ideal conditions and provide a hotter, more efficient burner flame.

A further object of the invention is to design a burner assembly of the type described, wherein only clean air from without the combustion chamber is mixed with the gaseous fuel so that there are no entrained fly ash particles or uncombusted material to clog the flame ports of the burner head.

Another object of the invention is to provide a gas burner which is shielded so that wet or damp refuse or garbage cannot clog the burner flame ports and smother the flame.

A further object of the invention is to provide a burner assembly wherein the flames of the burner are impinged directly upon a perforated shield so that the surrounding garbage is dried, ignited and combusted by the heat transferred thereby, as well as by direct contact with the flame.

Another object of the invention is to provide a highly efficient burner assembly which slowly and evenly dries, ignites, and consumes the garbage and refuse in the combustion chamber without releasing objectionable odors to the room in which the unit is housed.

A further object of the invention is to design a unitary burner assembly which can be repaired in place, or readily removed from the incinerator for repair, alteration or replacement, without dismantling the incinerator or removing the contents of the combustion chamber.

Another object of the invention is to provide a well-vented burner assembly which eliminates the possibility of unburned gas collecting in the combustion chamber and exploding.

A further object of the invention is to design a shielded burner assembly which can be conveniently and safely lit from outside the combustion chamber.

Another object of the invention is to provide a shielded burner assembly which includes an extension for supplying secondary or draft air from below the combustion chamber, thus avoiding the use of air from the combustion chamber which contains entrained particles which could clog the burner and burner shield.

A further object of the invention is to design a burner assembly of strong and durable construction which requires little maintenance and is economical to manufacture and install.

A still further object of the invention is to design a burner assembly in which the burner head is constructed

2

to deflect fly ash and the like from the flame ports, and which burns only sufficient gas to promote dehydration and support the combustion flame, thereby tending to eliminate smoke and odor problems.

With the above and other objects in view, the present invention consists in the combination and arrangement of parts, hereinafter more fully described, illustrated in the accompanying drawings, and more particularly pointed out in the appended claims, it being understood that changes may be made in the form, size, proportion, and minor details of construction, without departing from the spirit, or sacrificing any of the advantages of the invention.

In the drawings:

Fig. 1 is a side elevational view of my garbage disposal unit, the side wall thereof being broken away to show the burner assembly.

Fig. 2 is an enlarged, side elevational view of the burner assembly only.

Fig. 3 is a front elevational view thereof.

Fig. 4 is a fragmentary, elevational view of an extension member for admitting draft air to the shielded burner from below the combustion chamber.

Fig. 5 is a top plan view thereof.

Fig. 6 is an enlarged, sectional, elevational view of the burner head.

Referring now more particularly to the accompanying drawings in which I have shown the preferred embodiment of my invention, a letter I generally indicates an incinerator or garbage disposal unit of the down-draft type in which my burner assembly is installed, the unit being comprised of an insulated outer casing 9 with a cover 10, an inner casing 11 spaced from the outer casing 9 defining a perimetral air passage 12 and providing a combustion chamber 13 as usual.

A grate 14, actuated by a shaker finger 15 on a shaker rod 16, forms the floor of the chamber 13 and an ash drawer 17 is removably positioned beneath the grate. To permit the flow of air through the passage 12 to supply the top of the combustion chamber 13, the bottom of the incinerator (not shown) is open to the passage 12. A great portion of the air flowing upwardly through the passage 12 enters the combustion chamber 13 through perforations (not shown) in a wall 18, while the remaining portion thereof sweeps around the wall 18 to the stack 19.

A burner access opening 20 in the outer casing 9 is normally covered by a panel 21 which fits thereto in the manner shown, and an opening 22 is similarly provided in the inner wall 11. It will be observed that the burner assembly B (see Figs. 2 and 3) is provided with a substantially annular panel 23 which is mounted over the opening 22 and supports the assembly in position.

Fixed to the rear face of the panel 23 near the lower edge thereof is the head 24 of a tubular extension T 25, the head 24 being provided with flanges or legs 26 which may be welded to the rear face of the panel 23. The depending body portion of the T 25 is arranged to terminate just short of the grate 14 for a purpose which will be presently described.

Received in the upper end of the T 25 is a tapering tubular burner shield S which is provided with perforations 27 as shown. Supported within an opening (not shown) in the panel 23 through which it extends is a curved burner tube 29 which passes through the T 25 into the lower end of the shield S and carries a burner head 30 on the upper end thereof. The head 30 is specially designed to protect the angularly extending flame ports 31 which lead from the chamber 32 provided in the inner end of the burner, and to direct the flame to the wall of the shield S, and is annularly recessed intermediate its length as at 33.

The burner head 30 is formed with an enlarged, mushroom-type cap 34 which overhangs the flame ports 31 as shown to prevent fly ash and the like, which might fall through the perforations 27 in the shield S, from clogging the ports 31. It will be apparent that a portion of the flame from the ports will be impinged upon the sloped underwall 35 of the cap and deflected to the shield S, and that the remainder of the flames from the ports will be impinged directly upon the wall of the shield. The result of directing the flame to the wall of the shield is to form a hollow cylindrical wall flame above the burner which has direct contact with the material in the combustion chamber through the perforations 27. Moreover, the heat transferred by the wall of the shield S plays an important part in drying and igniting the surrounding refuse in the combustion chamber.

Mounted on the opposite end of the tube 29 within the passage 12 is a gas flow control valve 36 which controls the flow of gas to the tube 29 from the gas supply pipe 37 in accordance with a calibrated control 38. Inasmuch as the control and valve are conventional and form no part of the instant invention, they will not be described in further detail. A primary air port 39 is provided in the tube 29 and clean fresh air from the chamber 12 will be inspirated into the tube at this point and mixed with the gaseous fuel.

In order that the burner may be safely lit without the hand entering the combustion chamber, a lighter tube 40 is mounted in an opening 41 provided in the panel 23 opposite one of the perforations 27 in proximity to the burner head 30.

A vent tube 42, received in the upper end of the burner shield S, extends upwardly out of the combustion chamber 13 between the walls 11 and 18, and it will be apparent that any unburned gas is thus transmitted out of the combustion chamber and flows to the stack 19.

In operation, it will be apparent that it is unnecessary to light the burner before loading the combustion chamber 13, and thus permit smoke to escape to the room upon the loading thereof. With applicant's novel burner assembly, it is possible to first load the combustion chamber 13 with garbage, refuse and the like before lighting the burner. Then with the cover 10 closed, the control knob 38 is adjusted to permit gas to flow through the tube 29 to the burner head 30 and a match is struck and inserted into the tube 40 to light the burner. Only sufficient gas to provide a flame which will promote dehydration of the wet garbage and support combustion is burned so that outside smoke and odor problems are minimized. The incorporation of clean, fresh air with the gaseous fuel provides a hotter, more efficient flame than has heretofore been possible to obtain.

In view of the foregoing, it will be apparent that I have perfected a highly efficient and practical burner assembly, which while intended for use in garbage disposal units, will find widespread use in other fields. Accordingly, it is to be understood that I do not wish to limit myself to the use herein described, and intend that the appended claims cover various embodiments of the device within the spirit and scope of the invention.

What I claim is:

1. The combination with a downdraft incinerator comprising an outer casing, an inner casing within the outer casing and forming a combustion chamber, said inner and outer casings being spaced to provide an air supply passage therebetween, said inner casing being provided with an opening therethrough leading into said combustion chamber, of a burner assembly including a panel secured over said opening, a source of fuel gas supply, a mixing tube connected to said source of fuel gas supply and extending from said passage through said panel into said chamber, a burner head fixed to the end of said tube within the combustion chamber, said mixing tube

having an air port for inspirating clean air thereinto located within said passage, the outer casing having an access opening adjacent the opening in the inner casing, and a tube open to said air passage extending from said panel into said chamber and terminating above and adjacent said burner head to permit lighting of the burner head from without the combustion chamber.

2. The combination with a downdraft incinerator comprising an outer casing, an inner casing within said outer casing forming a combustion chamber and defining an air supply passage between the outer and inner casings, said inner casing having an opening near the upper end thereof to admit air from said passage to the chamber, of a mixing tube leading from said passage through said inner casing into said chamber below said admission opening, a source of gaseous fuel supply connected to one end of said mixing tube, a burner head connected to the opposite end of said mixing tube, said tube having air port means for inspirating clean air thereinto located within said passage, and a perforated shield for said burner head, said head including circumferentially spaced, upwardly inclined flame ports for directing the flame to said shield.

3. The combination with an incinerator comprising a casing forming a combustion chamber, the casing having an opening therein leading into said chamber, of a burner assembly including a panel secured over said opening, a fuel supply pipe extending from outside of said casing into the casing and being turned angularly to extend alongside said plate, a burner head fixed to the end of the pipe and entirely within the casing being disposed generally adjacent said panel, a tube through said panel open at both ends thereof, the end of said tube within said casing terminating adjacent said burner head to permit lighting thereof from without said chamber.

4. The combination with a downdraft incinerator comprising an outer casing, an inner casing within said outer casing forming a combustion chamber and spaced from the outer casing to define an air supply passage between the outer and inner casings, said inner casing having an air port near the upper end thereof to admit air from said passage to said chamber and an opening therebelow of a burner assembly including a panel secured over said latter opening, a gas supply tube open to the air supply passage extending inwardly from said panel into the chamber, a burner head fixed to the end of the tube adjacent the panel, and a perforated shield surrounding said head and having perforations therein adjacent to the head, said head having upwardly inclined flame ports and an overhanging cap thereabove with an upwardly inclined undersurface for deflecting flames laterally to the perforations in the shield to form a hollow cylindrical wall of flame along the inner wall of the shield.
